CHESTER K. BROOKS, OF CLEVELAND, OHIO, ASSIGNOR TO THE NATIONAL MALLEABLE CASTINGS COMPANY, OF CLEVELAND, OHIO, A CORPORATION OF OHIO.

FRICITION DRAFT-RIGGING.

1,183,837.

Specification of Letters Patent. Patented May 16, 1916.

Application filed April 27, 1912. Serial No. 695,521.

To all whom it may concern:

Be it known that I, CHESTER K. BROOKS, a citizen of the United States, residing at Cleveland, Cuyahoga county, Ohio, have invented a new and useful Friction Draft-Rigging, of which the following is a specification, reference being had to the accompanying drawings, in which—

Figure 1 is a plan, partly in section, of my draft rigging, showing its application to a railroad car; Fig. 2 is an elevation, partly in section; and Figs. 3, 4 and 5 show details thereof.

My invention relates to improvements in friction draft riggings and is particularly designed for use with the heavy cars now in service on the railways.

My improved draft rigging is adapted to absorb and to dissipate to a very high degree the shocks of buffing and draft, by reason of the frictional engagement of its parts.

Referring to the drawings—2 indicates a casing or housing, preferably cylindrical in form; the casing or housing 2 has enlarged portions 3 preferably formed integral therewith, which are rectangular in shape and the rear one of which is adapted to abut against the rear draft sill stops 4 which are attached to the draft sills 5 of the car structure. Seated within the rear of the casing 2 are the springs 6 and 7, the spring 7 being located within spring 6, and both of which abut at their rear ends against the rear end of the casing 2. The frictional elements are composed of a series of segments 8, which bear against the interior of the casing. The casing is preferably lined with a hardened steel bushing 9, which is held in the case by the bearing ring 10. The segments 8 are held against the casing by and are seated in the convolutions of a resilient helical wedging member 11, which has an inclined wedging face 12, which face 12 bears against the corresponding inclined face 13 of the segments.

14 and 15 are bearing blocks which abut against the foremost and rearmost segments 8, and against the front and rear of the helix 11, respectively. The outer surfaces of these blocks are flat, and the inner surfaces are provided with the stop shoulders 16 and 17, which form bearings for the end segments of the series, and also seats 18 and 19 against which the ends of the helix abut, parallel to the line of draft. The spring 6 abuts against

the rear face of the bearing block 15, and the front follower 20 bears against the front face of the bearing block 14. Within the helix 11 is a sleeve member 21 fitting snugly therein, and preferably secured to the front follower 20. The sleeve 21 forms a support for the helix and prevents its collapse when excessive wedging pressures are applied. On the inside of the sleeve 21 is a bearing 22 against which the forward end of the spring 7 bears.

The operation of the draft rigging is as follows: In buffing, the buffing pressure is transmitted to the front follower 20, which is caused to move rearwardly and to enter the casing 2, the rear end of the casing being held from rearward movement relative to the car by the rear stops 4 which are attached to the draft sills 5. The follower 20 transmits this pressure through the bearing block 14 to the helix 11, and by a wedging action from the helix 11 to the segments 8. This pressure is transmitted through all the convolutions of the helix 11 to all of the series of segments 8. As the helix moves rearwardly within the casing, its rearward movement is resisted by the spring 6 which bears against the rear end of the bearing block 15, and this resistance is transmitted through the helix 11 to the whole series of segments 8, causing a powerful frictional engagement between the exterior surfaces of the segments and the entire cylindrical surface of the casing, thus exhausting the force of the buffing shock. This frictional engagement of the segments and the interior surfaces of the casing increases progressively, since, as the helix 11 and segments 8 move rearwardly in the casing, the spring 6 bears with increasing pressure on the bearing block 15, and this pressure is transmitted thereby to the helix and to the frictional members as described. When the rigging is under draft, the casing 2 will move forwardly, and as the front follower 20 is held against forward movement by the forward draft sill stops 4, this forward action of the casing is resisted by the springs 6 and 7, the spring 6 forcing into wedging engagement the helix 11 and the segments 8 and 9, causing the same relative movement and progressively increasing frictional engagement between the segments and the casing as when the draft rigging is under buffing shock.

After buffing or draft the helix 11

acts as a positive releasing element and releases all the segments 8 except the rearmost segment, from wedging engagement with its coils and with the casing. This releasing 5 action of the helix is supplemented by a spring 7 which drives the sleeve forwardly and with it the front follower which permits the helix the more readily to relieve itself of the pressure which has been imposed upon it. It will be seen that as there 10 is no wedging engagement between the forward faces of the helix and the rear faces of the segments, that there can be no sticking together of these parts when the pressure 15 on the helix has been relieved, especially as the helix itself has the positive releasing action just described. The release of the wedging action between these parts will be practically simultaneous, since all of the 20 convolutions of the helix spread apart, to some slight extent, in a longitudinal direction, as soon as the pressure abates.

It is obvious to those skilled in the art that many changes may be made in the form 25 and arrangement of the various parts which I have described without departing from my invention, since

What I claim is:

1. In a friction draft rigging, a casing 30 having an internal cylindrical bearing surface, frictional members bearing against the casing, and having their outer faces concentric thereto, and having inclined inner faces, a helical wedging member having inclined 35 wedging and seating surfaces in its exterior convolutions adapted for the seating therein of said segments, a bearing block having on one side seating surfaces for a segment and for said helix, and a spring bearing against 40 the other side of said bearing block adapted to transmit pressure therethrough to said helix and to said frictional members.

2. In a friction shock-absorbing mecha-

nism, a friction member, a plurality of series of frictional shoes bearing against the 45 friction member, wedging faces on the frictional shoes, a helix having a wedging face co-acting with the wedging faces on the friction shoes, an incompressible and incompressible member adapted to hold the helix 50 in wedging engagement with said shoes, and a release spring co-operating with said helix to restore the parts to normal position after the pressure abates.

3. In frictional shock absorbing mechanism, a longitudinally extending friction member, friction shoes having friction faces in engagement with the friction member and having wedging faces, a wedge in the form of a helix having wedging faces engaging the wedging faces on the friction shoes, the friction wedge being substantially non-resilient in a radial direction whereby the length of movement of the wedges and friction shoes is substantially equal, and resilient means opposing the movement of the friction shoes and wedge.

4. In frictional shock absorbing mechanism, a longitudinally extending friction member, a plurality of friction shoes bearing frictionally against the friction member and movable longitudinally relatively thereto, wedging non-frictional faces on the friction shoes, and a helix having a wedging non-frictional face coacting with the wedging non-frictional faces of the frictional shoes, and means for holding the helix substantially from movement radially, whereby the helix is always held firmly against the wedging faces of the friction shoes, and resilient means opposing the movement of the friction shoes and wedge.

CHESTER K. BROOKS.
